UNITED STATES PATENT OFFICE

2,505,930

LOAD TRANSFER DEVICE

Ray Cyrus Yeoman, Lufkin, Tex., assignor to
 Texas Foundries, Inc., Lufkin, Tex., a corpora-
 tion of Texas

Application March 21, 1945, Serial No. 583,945.

4 Claims. (Cl. 94—8)

1

This invention relates to load transfer devices and more particularly to devices for transferring loads between adjacent slabs of concrete or the like.

One of the objects of the invention is to provide a simple and inexpensive load transfer device for transmitting vertical loads between adjacent slabs and for limiting relative horizontal movement of the slab faces.

Another object is to provide a load transfer device formed of substantially identical plates to be imbedded in the slabs respectively and having engaging parts thereon to prevent separation of the plates while permitting limited relative sliding movement thereof.

Still another object is to provide a load transfer device in which the plates are formed with openings therethrough and with hooks to extend through the openings in the opposite plates so that separation of the plates is prevented while relative sliding movement thereof is permitted.

The above and other objects and advantages of the invention will be more readily apparent from the following description when read in connection with the accompanying drawing, in which—

Figure 1 is a partial horizontal section through a pair of adjacent slabs connected by a load transfer device embodying the invention;

Figure 2 is a partial vertical section on the line 2—2 of Figure 1; and

Figure 3 is a perspective view of one of the plates.

As shown in Figures 1 and 2 the load transfer device of the invention connects a pair of concrete slabs 10 and 11 having a filler strip 12 between their adjacent faces. The filler strip 12 may be any desired type of expandable material such as asphaltic material, compressed wood or fabricated metal joint strips.

The load transfer device is formed by a pair of identical plate members 13 imbedded in the slabs respectively and which may have openings 14 therethrough securely to fasten the plates in the slabs. Each of the plates projects beyond the end of the slab in which it is imbedded into the opposite slab. A strip of yielding material 15, such as rubber or asphaltic material, is arranged opposite the end of each plate to permit yielding movement thereof in the opposed slab under expansion or contraction of the slabs.

In order to secure the plates together each of the plates is formed in its projecting end portion with a series of openings 16 therethrough. Preferably the openings are formed by punching out strips of metal from the plates which are then

bent outwardly from the plate and turned back at the end to provide a hook member 17.

In assembling the plates, the hook member 17 of each plate extends through the opening 16 in the other plate and hooks over the other plate surface so that the plates are held together against lateral separation. If desired, the hook members and plates may be greased to facilitate sliding and to prevent adhesion of concrete thereto. The hook members and openings are long enough to permit relative sliding of the plates without separation.

After the plates are assembled, the openings 16 between the hook portions are filled with plastic material such as rubber, asphalt composition or the like, as shown at 18. This material may be inserted as preformed plugs or may be pressed into the openings as a plastic mass to fill them as indicated. During pouring of the concrete this material prevents the concrete from filling the openings and will compress when the slabs expand to accommodate closing of the joint.

In use with the plate members installed in the slabs as shown any vertical loads on one of the slabs will be transmitted through the plate member imbedded therein and directly through the overlapping portions of the plates or through the hook members, depending upon the direction of the load, to the opposite slab. As the slabs expand and contract the projecting end portions of the plates may move in the opposite slabs by compressing or moving away from the yielding material 15 and without disengaging the hook portions 17 from the plates. At the same time the hook portions 17 will compress or relieve the pressure on the yielding material 18. It will be understood that the hooks 17 and openings 16 are made long enough to accommodate the expected amount of movement in response to expansion or contraction of the slabs without disengaging. If the slabs should tend to separate to an excessive extent, the hook members will engage the opposite plates at the ends of the openings 16 therethrough to prevent excessive separation of the slabs which might move their faces out of sealing engagement with the filler strips 12.

While one embodiment of the invention has been shown and described in detail, it will be understood that this is illustrative only and is not intended as a definition of the scope of the invention, reference being had for this purpose to the appended claims.

What is claimed is:

1. A load transfer device for use with adjacent slabs of concrete or the like comprising a pair

of plate members adapted to be imbedded in the slabs respectively with their ends projecting beyond the slabs and lying in face to face relationship, each of the plates having an opening therethrough and an outwardly extending hook member of smaller horizontal section than the opening adjacent one end of the opening, the hook member on each plate extending through the opening in and hooking over the other plate to prevent separation of the plates while permitting relative sliding thereof the opening being filled with yielding material at one side of the hook member.

2. In combination with adjacent slabs of concrete or the like a load transfer comprising a pair of plate members imbedded in the slabs respectively with their ends projecting beyond the slabs and lying in face to face relationship, the projecting end of each plate extending into the opposite slab, a strip of yielding material between the projecting end of each plate and the slab to permit relative movement therebetween, one of the plates having an opening therein, and a part on the other plate smaller than the opening and extending therethrough to hold the plates together while permitting relative sliding movement thereof.

3. In combination with adjacent slabs of concrete or the like a load transfer device comprising a pair of plate members imbedded in the slabs respectively with their ends projecting beyond the slabs and lying in face to face relationship, the projecting end of each plate extending into the opposite slab, a strip of yielding material between the projecting end of each plate and the slab to permit relative movement therebetween, each of the plates being formed with an opening through its projecting end portion, and each of the plates being formed with an outwardly extending hook member adjacent the opening therethrough to extend through the opening in

and hook over the other plate to hold the plates together while permitting relative sliding thereof.

4. In combination with adjacent slabs of concrete or the like a load transfer device comprising a pair of plate members imbedded in the slabs respectively with their ends projecting beyond the slabs and lying in face to face relationship, the projecting end of each plate extending into the opposite slab, a strip of yielding material between the projecting end of each plate and the slab to permit relative movement therebetween, each of the plates being formed with an opening through its projecting end portion, and each of the plates being formed with an outwardly extending hook member adjacent the opening therethrough of smaller horizontal section than the opening to extend through the opening in and hook over the other plate to hold the plates together while permitting relative sliding thereof, the openings being filled with plastic material at one side of the hooks extending therethrough which is adapted to be compressed as the plates move toward each other.

Certificate of Correction

Patent No. 2,505,930

May 2, 1950

RAY CYRUS YEOMAN

It is hereby certified that error appears in the printed specification of the above numbered patent requiring correction as follows:

Column 3, line 15, after the word "transfer" insert *device*;
and that the said Letters Patent should be read as corrected above, so that the same may conform to the record of the case in the Patent Office.

Signed and sealed this 3rd day of October, A. D. 1950.
